SWITCH LOCK FOR RAILWAYS

Lee J. Cotten, Chicago, Ill.

Refiled for abandoned application Serial No. 494,320, November 8, 1930. This application February 21, 1934, Serial No. 712,431

6 Claims. (Cl. 70—128)

This invention relates to an improved switch lock for railways, and has for one of its principal objects the provision of a lock for railway switches and similar devices which will comprise a self-contained lock, eliminating locks and other appurtenances.

One of the important objects of this invention is the provision of a mechanism for use with a railway switch which will lock the switch lever in desired position either open or closed, and which can be made in duplicate for locking in both open and closed position, if desired.

Another important object of the invention is to provide in a railway switch lock or the like a key-operated locking mechanism which will positively eliminate any chance of accidentally leaving the device unlocked, and which will further be so constructed that the key cannot be withdrawn unless the apparatus is in locked position, thereby eliminating any possibilities of accidents or wrecks owing to open switches or to switches being inadvertently or maliciously thrown when left unlocked.

A still further important object of the invention is the provision in a switch lock for railways of a means which is absolutely fool-proof and also proof against tampering or the like, and which further will operate in any weather, not being subject to conditions of sleet, ice or snow which often cause great trouble and misfortune.

Other and further important objects of the invention will be apparent from the disclosures in the accompanying drawing and following specification.

35 The invention, in a preferred form, is illustrated in the drawing and hereinafter more fully described.

In the drawing:

Figure 1 is a vertical elevation of the improved switch lock of this invention.

Figure 2 is a vertical view, partly in section, showing the interior construction of the device.

Figure 3 is another vertical view taken at right angles to the showing in Figure 2.

45 Figure 4 illustrates a slight modification of the invention.

As shown in the drawing:

The reference numeral 10 indicates generally the base of the improved switch locking device of this invention, having an integral upstanding casing 12 and also an integral flange 14 spaced away from the casing and a sufficient distance to allow of the dropping of a switch-operating lever thereinto. The switch-operating lever is

then adapted to be locked in position by means of a withdrawable latch bolt 16.

The locking element itself forms the outer end of a member 18 which is mounted in a vertical position in the casing 12 and is slidably and pivotally supported on integral lugs 20 which extend sidewise into slots 22 formed in the casing 12 for their reception.

The lower end of the member 18 is curved inwardly and slightly upwardly as shown at 24, this being adapted to cooperate with the cammed face of a plunger or weight 26 which is adapted to move vertically in the casing 12.

The upper end of the slideable weight 26 is also cammed as shown at 28, and it will be evident that a downward movement of this weight will force the toe 24 of the member 18 inwardly, and somewhat downwardly causing this member to pivot about the points 20, and allowing its upper rearwardly-flared end to fit into the space provided by the cam face 28 of the weight 26.

In this way, the latch element 16 is withdrawn allowing the switch-operating lever to be raised.

A lock 30 is countersunk into a suitable opening in the face of the plunger 26, and a key 32 is provided for operating the lock, the key itself sliding in a slot 34 formed in the casing when the plunger drops or is raised.

The lock itself is provided with a retractable latch 36 best illustrated in Figure 3, which fits into a suitable opening 38 formed in the housing 12, this latch being spring-impelled forwardly so that when the plunger is raised, it will be held in raised position until the latch is again withdrawn by operation of the key.

In order to raise the plunger 26 after the same has been dropped, a treadle 40 is provided pivoted at 42 in the casing 12, and having an inner projecting end 44 which cooperates with the lower rounded end 46 of the plunger 26 as best shown in the dotted lines in Figure 3. The lock 30 is of a well-known construction such that when the locking element 36 is in retracted position, the key cannot be turned and the slot 34 is of a width not much greater than the diameter of the key shank so that obviously the key cannot be withdrawn from the lock when the plunger is in dropped position.

A slight modification is illustrated in Figure 4 wherein a lock casing 50 is mounted directly in the casing 52 of the apparatus, the lock 50 having a retractable latch 54 which operates in a suitable opening formed in the plunger 56. A weather guard 58 is provided for the keyhole of the lock 50. This eliminates any slideable motion

of the key in the casing, while at the same time providing all of the advantages of the first construction, namely the retaining of the key in the lock until such time as the device has been 5 properly secured.

It will be seen that herein is provided a lock for railway switches of the type commonly known as ground switches, which eliminates the use of the ordinary padlock, and forms a much more 10 positively acting apparatus, and which, further, is entirely safe, as by its use is eliminated the possibilities of open switches.

I am aware that many changes may be made and numerous details of construction varied 15 throughout a wide range without departing from the principles of this invention, and I, therefore, do not purpose limiting the patent granted hereon otherwise than as necessitated by the prior art.

20 I claim as my invention:

1. A railway switch lock, comprising a housing 25 associated with a switch lever, a recess in the housing for the reception of the end of the lever, a locking lug pivoted adjacent said recess for preventing unauthorized movement of the lever, and means for locking said lug in switch 30 lever retaining position, said means comprising a gravity actuated plunger, means on the plunger for operating the lug, and further means on the plunger adapted to lock the same in position.

2. A railway switch lock, comprising a housing 35 associated with a switch lever, a recess in the housing for the reception of the end of the lever, a locking lug pivoted adjacent said recess for preventing unauthorized movement of the lever, and means for locking said lug in switch 40 lever retaining position, said means comprising a cam face on the lug, and further means adapted to lock the lug in position, said last-named means comprising a cammed weight operatively associated with the lug and a key-operated lock for maintaining said weight in locking position in the housing.

3. A railway switch lock, comprising a housing 45 associated with a switch lever, a recess in the housing for the reception of the end of the lever, a locking lug pivoted adjacent said recess for preventing unauthorized movement of the lever, and means for locking said lug in switch lever re-

taining position, said means comprising a plunger, cammed faces on the plunger for operating the lug, and further means on the plunger adapted to lock the same in position, said means comprising a key-operated lock.

4. A railway switch lock, comprising a housing 5 associated with the switch lever, a recess in the housing for the reception of the end of the lever, a locking lug pivoted adjacent said recess for preventing unauthorized movement of the lever, and means for locking said lug in switch 10 lever retaining position, said means comprising a gravity operated cammed weight, cammed faces on the lug adapted to cooperate with the weight, and further means on the weight adapted to lock the same in position, said further means comprising a key-operated lock, and means for returning the parts to normal locked position, said means comprising a manually operated foot lever.

5. A railway switch lock, comprising a housing 15 associated with the switch lever, a recess in the housing for the reception of the end of the lever, a locking lug pivoted adjacent said recess for preventing unauthorized movement of the lever, 20 and means for locking said lug in switch lever retaining position, said means comprising a weight loosely and slidably mounted in the housing against said lug, means on the weight for operating the lug, and further means on the weight adapted to lock the same in position, said last-named means comprising a key-operated lock for maintaining said weight in raised position in the housing.

6. A railway switch lock, comprising a housing 25 associated with the switch lever, a recess in the housing for the reception of the end of the lever, a locking lug pivoted adjacent said recess for preventing unauthorized movement of the lever, and means for locking said lug in switch 30 lever retaining position, said means comprising a weight slidably in the casing, cam faces on the weight for operating the lug, and further means on the weight adapted to lock the same in position, said further means comprising a key-operated lock in the weight, said housing having a slot adjacent the weight for slidable reception of the key.

LEE J. COTTON.
